UNITED STATES PATENT OFFICE.

WILLIAM BOWDEN, OF MANCHESTER, ENGLAND.

LIQUID-FUEL-SUPPLY APPARATUS FOR INTERNAL-COMBUSTION ENGINES.

Application filed November 3, 1920. Serial No. 421,517.

To all whom it may concern:

Be it known that I, WILLIAM BOWDEN, a subject of the King of Great Britain and Ireland, and a resident of Manchester, in the county of Lancaster, England, have invented certain new and useful Improvements in Liquid-Fuel-Supply Apparatus for Internal-Combustion Engines, of which the following is a specification.

This invention relates to liquid-fuel supply apparatus for internal combustion engines, and to apparatus of the kind wherein the liquid-fuel is raised by suction from a main supply tank or chamber into a supplementary vessel whence the liquid fuel flows by gravity to an auxiliary vessel and from the latter to the carburettor of the engines, suitable valves being provided for controlling the liquid inlet to and outlet from said supplementary vessel and the connection of the latter with a source of suction and the atmosphere.

In liquid-fuel supply apparatus of the kind referred to the valves aforesaid have hitherto been operated by a float, which rises and falls with the level of the liquid in the supplementary chamber, through the medium of mechanical means. The main object of this invention is to provide improved float-controlled means for operating the valves whereby the work to be performed by the float or floats is reduced to a minimum and the operation of the valves is rendered certain and the apparatus functions with precision. A further object is to provide in such apparatus means for metering the total quantity of liquid-fuel supplied.

According to the invention the valves of a liquid-fuel supply apparatus of the kind referred to are operated by electro-magnetic devices the circuits of which are controlled by float-actuated switches.

In the accompanying drawings, Fig. 1 is a central vertical section of one form of liquid-fuel supply apparatus embodying the invention, Fig. 2 is an enlarged sectional view of one of the valves hereinafter more particularly referred to, Fig. 3 is a diagram of the electrical connections and Fig. 4 is a diagrammatic view illustrating the general arrangement of the apparatus for supplying liquid fuel to the carburettor of an internal combustion engine.

Referring to the drawings, the liquid-fuel supply apparatus comprises an upper chamber 1 of predetermined capacity and herein-

after referred to as the measuring chamber, and a lower receiving chamber 2. The measuring chamber 1 is provided with liquid inlet 3 which is connected by means of a pipe 3^a with the main supply tank *w*, Fig. 4, which is arranged below the level of the measuring chamber 1 and on a level with or below the carburettor *x*. The measuring chamber 1 has an outlet 4 to the receiving chamber 2 which is provided with a draw-off outlet connected by a pipe 2^a with the float chamber *x*¹ of the carburettor *x*.

Within the measuring chamber 1 are arranged needle valves 5 and 6 for controlling the inlet 3 and outlet 4 respectively. The valves 5 and 6 are operatively connected by a rocking lever 7 pivoted at 8 to lugs 9 on the underside of the cover 10 of the measuring chamber 1. The ends of the arms of the rocking lever 7 are bifurcated and coact with and between collars 5^a, 5^b and 6^a, 6^b on the stems of the valves 5 and 6 respectively, in such manner that when the valve 5 is raised and opened, valve 6 is depressed and closed, and vice versa. The upper ends of the stems of the valves 5 and 6 pass through stuffing boxes 5^c, 6^c into tubular extensions 11 and 11^a on the cover 10 of the measuring chamber 1 and are formed with, or connected to, the plungers or cores 12 and 13 of solenoids 14 and 15 arranged on the extensions 11 and 11^a respectively.

The circuits of the solenoids 14, 15 are controlled by floats 16, 17 respectively. The lower float 16 operates in a casing 18 arranged in a chamber 19 disposed in the lower part of the measuring chamber 1 and extending into the receiving chamber 2. The casing 18 communicates at the bottom with the chamber 19 by holes 18^a, and at the top it communicates with the measuring chamber 1 by holes 18^b. The chamber 19 communicates with the inlet 3 and with the measuring chamber 1 by passages 19^a at the top and holes 19^b in its wall near the base of the measuring chamber. The chamber 19 also communicates with the inlet 3 by an opening 19^c. The lower end of the float 16 is provided with a stem 20 which passes freely through a central hole in the bottom of the casing 18 and carries a switch-member 21 which is adapted to coact with contacts 22, 22^a attached to the underside of the base of the casing 18 and to which the conductors 23, 23^a of the solenoid 14 are

connected by being clamped between same and the base of the casing. The upper end of the float 16 carries guide stems 20^a which pass through some of the holes 18^b to guide the float in its rising and falling movements.

The upper float 17 is mounted in a casing 24 carried by the cover 10 and communicating with the measuring chamber 1 by means of holes 24^a in its wall and holes 24^b in its lower end. The lower end of the float 17 is provided with a depending stem 25 which passes freely through a central hole in the base of the casing 24 and carries a switch member 26 adapted to co-act with contacts 27, 27^a in the circuit of the solenoid 15 and also having inclined or upturned ends. The upper end of the float 17 carries guide stems 25^a which pass through holes in a perforated partition 28 to guide the float in its movements.

The upper ends of the tubular extensions 11, 11^a on which the solenoids 14, 15 are mounted communicate by passages 29, 29^a with the upper float casing 24. The upper end of the extension 11 also communicates with the atmosphere by a connection 30 and the upper end of the extension 11^a communicates by a pipe 31 with a source of suction 30 which may be the or one of the cylinders of the engine which is supplied by the apparatus. Conveniently, the pipe 31 leads to the induction pipe γ of the carburettor. The atmosphere connection 30 and the suction connection 31 are controlled by valves 32, 33 carried by stems 12^a, 13^a on the cores 12, 13 of the solenoids 14, 15.

As shown in Fig. 3, one end of the winding of each of the solenoids 14, 15 is connected to a common terminal 34 on the cover 10, to which terminal one terminal of a battery 35 or other source of electrical energy is also connected by a lead 36. The other ends of the windings of the solenoids 14, 15 are connected to terminals 37, 38 respectively. The other terminal of the battery 35 is connected by a lead 39 to a conductor 40 carrying two terminals 41, 42. The conductor 23 connects terminal 37 to contact 22 and conductor 23^a connects contact 22^a to terminal 41. Terminal 38 is connected by conductor 43 to contact 27, and contact 27^a is connected by conductor 44 to terminal 42. Thus the circuit through solenoid 14 is from battery or source 35 by lead 36, terminal 34, the winding of solenoid 14, terminal 37, conductor 23, contact 22, switch-member 21 carried by lower float 16, contact 22^a, conductor 23^a, terminal 41, conductor 40 and lead 39 back to the battery or source 35. The circuit through solenoid 15 is from battery or source 35, by lead 36, terminal 34, the winding of solenoid 15, terminal 38, conductor 43, contact 27, switch-member 26 carried by upper float 17, contact 27^a, conductor

44, terminal 42, conductor 40 and lead 39 back to the battery or source 35.

An electrically operated registering device of any known and appropriate construction is provided in one or other of the circuits for the purpose of registering the number of times the measuring or receiving chamber is filled. In the diagram of Fig. 3, a device 45 is indicated in the circuit of the solenoid 15 between terminal 38 and contact 27, but it will be understood that the device may be arranged in any other position in the circuit or in the circuit of the solenoid 14.

The operation of the apparatus is as follows:—

Assuming the measuring vessel 1 to be filling, the valves 5, 6, 32 and 33 and the rocking lever 7 will be in the positions shown in Fig. 1, and measuring chamber 1 will be open to the liquid inlet 3 and to the pipe 31 communicating with the source of suction and cut off from receiving chamber 2 and the atmosphere. Measuring chamber 1 is thus put under a reduced pressure and liquid is drawn into the chamber through the pipe 31 from the main supply tank ν . On the liquid rising in the chamber 1 to a predetermined level and the upper float 17 being lifted by the liquid which passes into the casing 24, the switch-member 26 co-acts with contacts 27, 27^a, thus closing the circuit through the solenoid 15 and the registering device 45. On the closing of this circuit, the device 45 is operated and the valves 6 and 33 are raised to open the outlet 4 to the receiving chamber 2 and cut off measuring chamber 1 from the source of suction, respectively, valves 5 and 32 being simultaneously depressed by the action of the rocking lever 7 to close the liquid inlet 3 and open the atmosphere connection 30, respectively, when measuring chamber now being isolated from the source of suction and put under atmospheric pressure, the liquid in measuring chamber 1 flows under gravity into the receiving chamber 2. On the emptying of receiving chamber 1 the lower float 16 falls and switch-member 21, contacts with contacts 22, 22^a completing the circuit through solenoid 14 which then lifts valves 5 and 32 to open the liquid inlet 3 and close the atmosphere connection 30, respectively, valves 6 and 33 being simultaneously depressed by rocking lever 7 to close outlet 4 to receiving chamber 2 and again put measuring chamber 1 in communication with the source of suction, respectively, when the cycle of operation is repeated.

In order to ensure the efficient closing of the several valves, the valves 32, 33 may, as shown better in Fig. 2 and exemplified in connection with the valve 33, be mounted on the stems 12^a, 13^a so as to be capable of limited movement relatively thereto. Conveniently, the valves are recessed to fit on 130

- the ends of the stems and are connected thereto by cross-pins 46 co-operating with slotted holes 47 in the wall of the recessed part and are acted upon by springs 48 arranged between them and the cores 12, 13.
- In some cases, the valve 32 for controlling the atmosphere connection 30 may be dispensed with and the measuring chamber 1 be continuously in communication with the 10 atmosphere, the connection 30 in such cases being so proportioned that when the suction connection 31 is opened a partial vacuum is created in the measuring chamber.
- 15 It will be obvious that instead of the switch members 21 and 26 being carried and actuated by separate floats, both switch members may be carried and actuated by a single float.
- 20 What I claim as my invention, and desire to secure by Letters Patent is:—
1. Liquid-fuel supply apparatus comprising in combination, a vessel provided with an inlet and an outlet for the liquid, an atmosphere connection, and a connection adapted to be connected with a source of suction; a receiving chamber adapted to receive liquid from said vessel by way of said outlet; valves adapted to open said liquid 25 inlet and said suction connection to said vessel and close the outlet therefrom to said receiving vessel, and vice versa; electromagnetic devices arranged in electrical circuits for operating said valves; switches adapted to be actuated by variations in the 30 level of the liquid in said vessel to control the circuits of said electromagnetic devices and an electrical registering device inserted with one of said switches for registering 35 the filling or emptying of said vessel.
  2. Liquid-fuel supply apparatus comprising in combination, a vessel provided with an inlet and an outlet for the liquid, an atmosphere connection, and a connection 40 adapted to be connected with a source of suction; a receiving chamber adapted to receive liquid from said vessel by way of said outlet; valves adapted to open said liquid inlet and said suction connection to said vessel and close said atmosphere connection to said vessel and said outlet therefrom to 45 said receiving vessel, and vice versa; electromagnetic devices arranged in electrical circuits for operating said valves; switches adapted to be actuated by variations in the level of the liquid in said vessel to control 50 the circuits of said electromagnetic devices; and an electrical registering device in circuit with one of said electromagnetic devices for registering the filling or emptying 55 of said vessel.
  3. Liquid-fuel supply apparatus comprising in combination, a vessel provided with an inlet and an outlet for the liquid, an atmosphere connection, and a connection 60 adapted to be connected with a source of suction; a receiving chamber adapted to receive liquid from said vessel by way of said outlet; valves adapted to open said liquid inlet and said suction connection to said vessel and close said atmosphere connection to said vessel and said outlet therefrom to 65 said receiving vessel, and vice versa; electromagnetic devices arranged in electrical circuits for operating said valves, switches adapted to be actuated by variations in the level of the liquid in said vessel to control the circuits of said electro magnetic devices, and an electrical registering device in circuit 70 with one of said electro magnetic devices for registering the filling or emptying of said vessels.
  4. Liquid-fuel supply apparatus comprising in combination, a vessel provided with inlets and outlets, valves controlling said inlets and outlets, electro magnetic devices arranged in electrical circuits for operating said valves, switches adapted to be actuated by variations in the level of the liquid in said vessels to control the circuits of said electro magnetic devices, and an electrical registering device in circuit 75 with one of said electro magnetic devices for registering the filling or emptying of said vessels.
  5. A liquid-fuel supply apparatus comprising in combination a measuring vessel provided with inlets and outlets, valves controlling said inlets and outlets, electro magnetic devices arranged in electrical circuits for operating said valves, switches adapted to be actuated by variations in the level of the liquid in said vessels to control the circuits of said electro magnetic devices, and an electrical registering device in circuit 80 with one of said electro magnetic devices for registering the filling or emptying of said vessels.
  6. In a liquid-fuel supply apparatus, a measuring vessel provided with an inlet for the liquid and an opening to the atmosphere, aligned valves for said inlet and opening, a stem connecting said valves and of proper length to close one valve when the other is open, said vessel being further provided 85

with suction and outlet opening, alined valves controlling the suction and outlet openings, a stem connecting the last mentioned valves and of a length sufficient to open one of the valves when the other is closed, a rocking lever connecting said stems whereby one of the stems moves in one direction simultaneously with the movement of the other stems in the opposite direction to alternately effect opening and closing of the inlet and outlet, solenoid cores each mounted on a respective stem, solenoids surrounding said cores, and float controlled means for selectively energizing said solenoids.

7. In a liquid-fuel supply apparatus, a measuring vessel provided with an inlet for the liquid and an opening to the atmosphere, alined valves for said inlet and opening, a stem connecting said valves and of proper length to close one valve when the other is open, said vessel being further provided with suction and outlet opening, alined valves controlling the suction and outlet openings, a stem connecting the last mentioned valves and of a length sufficient to open one of the valves when the other is closed, a rocking lever connecting said stems whereby one of the stems moves in one direction simultaneously with the movement of the other stems in the opposite direction to alternately effect opening and closing of the inlet and outlet, solenoid cores each mounted on a respective stem, solenoids surrounding said cores, a low level float in said vessel, a high level float in said vessel, circuit closers arranged for respective closing by the upward movement of the high level float and downward move-

ment of the low level float, and electrical connections between the respective circuit closers and the respective solenoids.

8. In a liquid-fuel supply apparatus, a measuring vessel provided with an inlet for the liquid and an opening to the atmosphere, alined valves for said inlet and opening, a stem connecting said valves and of proper length to close one valve when the other is open said vessel being further provided with suction and outlet opening, alined valves controlling the suction and outlet openings, a stem connecting the last mentioned valves and of a length sufficient to open one of the valves when the other is closed, a rocking lever connecting said stems whereby one of the stems moves in one direction simultaneously with the movement of the other stems in the opposite direction to alternately effect opening and closing of the inlet and outlet, solenoid cores each mounted on a respective stem, solenoids surrounding said cores, a low lever float chamber in the bottom of said vessel and having port communication therewith, a high level float chamber at the top of said vessel and having port communication therewith, floats in said chambers, a circuit closer below each of said chambers, the respective circuit closers being arranged to close by the upward movement of the float in the upper chamber and the downward movement of the float in the lower chamber, and electrical connections between the circuit closers and the respective solenoids.

In witness whereof I have hereunto set my hand.

WILLIAM BOWDEN.
